UNITED STATES PATENT OFFICE.

JACOB B. SCHMIDT, OF MILWAUKEE, WISCONSIN.

BOX-BLANK MACHINE.

1,426,608.

Specification of Letters Patent. Patented Aug. 22, 1922.

Application filed January 17, 1921. Serial No. 437,835.

To all whom it may concern:

Be it known that I, JACOB B. SCHMIDT, a citizen of the United States, and resident of Milwaukee, in the county of Milwaukee and 5 State of Wisconsin, have invented new and useful Improvements in Box-Blank Machines, of which the following is a description, reference being had to the accompanying drawings, which are a part of this specification.

This invention relates to certain new and useful improvements in box blank forming machines and refers more particularly to that part of a machine of this character in 15 which the securing folds of the blanks are formed.

Heretofore, the securing folds or tab portions of box blanks have been formed by hand after the blanks have been scored to 20 form fold or crease lines, which is a tedious operation and necessitates the employment of extra help.

Hence, with this and other objections in 25 mind, my invention has for one of its objects to provide means whereby the box blanks have the securing folds formed thereon by mechanical means whereby, with the aid of but a single operator, who feeds the blanks to the machine, the output of a plant 30 may be greatly increased.

Another object of this invention is to provide a machine for mechanically forming the securing folds on box blanks in which the blanks may or may not be previously 35 scored along the bend line of said securing folds and one which is capable of ready adjustment to accommodate blanks of different shapes and sizes.

With the above and other objects in view 40 which will appear as the description proceeds, my invention resides in the novel construction, combination and arrangement of parts substantially as hereinafter described and more particularly defined by 45 the appended claims, it being understood that such changes in the precise embodiment of the herein disclosed invention may be made as come within the scope of the claims.

In the accompanying drawings, I have 50 illustrated one complete example of the physical embodiment of my invention constructed according to the best mode I have so far devised for the practical application of the principles thereof, and in which:

55 Figure 1 is a side view of a machine embodying my invention;

Figure 2 is a fragmentary view part in section and part in elevation taken on the plane of line 2-2 of Figure 3;

Figure 3 is a top plan view of my improved machine;

Figure 4 is a perspective view of one of the fold forming plates employed in connection with the machine;

Figure 5 is a view taken transversely 65 through Figure 4 on the line 5-5; and

Figure 6 is a sectional view taken transversely through Figure 4 on the line 6-6.

Referring now more particularly to the accompanying drawings in which like numerals designate like parts throughout the several views:

The numeral 5 designates a supporting standard having secured thereon two opposed elongated bearing carrying members 75 6 and 7 having, medially secured thereto, a platform 8 along which the blanks to be formed with securing folds are fed. The platform 8 has a number of spaced openings 9 extending thereacross, and journaled 80 in the bearing members 6 and 7 in register with the openings 9 with their uppermost faces substantially in alignment with the top face of the platform 8 are feed rollers 10, said feed rollers having the ends of their 85 supporting shafts 11 journaled in the bearings 6 and 7. Fixed to each shaft 11, medially between its roll 10 and the bearing member 7 is a sprocket wheel 12. The sprocket wheels 12 are connected together 90 by a continuous chain 13 engaged therewith. The sprocket chain is held in engagement with the center sprocket wheels 12 by an idler wheel 14 secured to the bearing member 6 as best shown in Figure 2, and the 95 upper run of the chain is held taut by an idler wheel 15 secured to the bearing member 7 on a plane above the rolls 10. One of the shafts 11 has its end extended beyond the bearing member 6 to receive a pulley 100 16 which is drivingly connected with an electrical motor 17 mounted on the frame 5 by a belt connection 18.

Fixed to the shaft 11, carrying the pulley 16, is a gear wheel 19 which is adapted to 105 mesh with a gear wheel 20 fixed to the shaft 21 on a feed roll 22. The feed roll 22 is one of a series arranged above the lower rolls 10 and adapted to be yieldingly urged into engagement with the lower rolls 110 10 by adjustable spring means 23. All of the shafts 21 have their ends adjacent the

bearing member 6 extended therebeyond to receive drive sprockets 23 which are connected for simultaneous rotation by a sprocket chain 25, the lower run of said 5 chain passing over an idler wheel 26 and the medial portion of the upper run being retained in engagement with the two center sprocket wheels by an idler wheel 27. With this construction, the rotation of the first 10 roller 22, due to its gear connection with the adjacent lower roll 10, also imparts a like rotation to the remaining upper rollers.

The two upper end rolls 22 are in the 15 form of a continuous cylinder similar to the lower rolls, and the intermediate rolls are formed by spaced wheels or pulleys carried by the intermediate shafts 21. The intermediate roll adjacent the first upper roll 20 consists of two wheels or pulley members 29 and the other intermediate roll consists of a central wheel or pulley 30, similar to the other wheels 29, and two end wheels or pulleys 31 having their inner peripheral edges beveled, as at 32, for the purpose to 25 be hereinafter described. Connecting the bearing members 6 and 7, between the first two rolls and the second and third rolls are two shafts 33 and 34, respectively, and adjustably secured to said shafts near each 30 end are depending bracket members 35 having their lower ends secured to plate members 36. Said plate members 36 engage the platform 8 near the sides thereof and are capable of adjustment to vary the distance 35 therebetween by loosening the binding means 37 which secure the bracket members to the rods 33 and 34.

Centrally depended from the shaft 33 is 40 a bracket member 38 having two rollers 39 carried thereby for engagement with the blanks as they are fed through the machine, and secured to the rod 34, in spaced relation, are two similar bracket members 40 having rollers 41 carried thereby for engagement 45 with the blanks to retain the same flat on the platform.

Adjustably mounted in each bearing member 6 and 7, intermediate the last two rolls, are two jack-screws 42 having a transverse 50 plate 43 secured to their lower ends and adapted to be adjustably suspended above the platform 8. The inner edge of said plate 43 is curved or rounded as at 44 to guide the blank therebeneath as they are fed through the machine by the coacting feed rolls.

Each plate 36 has a reduced portion 45 of 60 a width substantially equal to the width of the securing fold 46 to form the blanks fed through the machine and said reduced portion extends to a point 47 and its depth decreases until at point 47 it is substantially nil. The adjacent edge of the plate then curves over, as at 48, to point 49 when the 65 same forms an outer edge having its top

point 50 extended laterally beyond its lower point 51. With this construction, a plurality of blanks are placed upon the receiving table 52 which has two adjustable guides 53 extended thereover and said 70 blanks may, if desired, be provided with scoring 54 along the line where the same are to be folded.

An operator then slides the blanks from the pile upon table 52 beneath the first set 75 of feed rollers, one at a time and the first feed rollers progress the blank through the machine. The side edges of the blank pass over the reduced portion 45 of each plate 80 36 and before the first set of feed rollers 30 relinquish their grip upon the blank, the second set continue the feeding of the blank. The upper roll of the second set consists of the two wheels 29 which are positioned adjacent the plate 37 in alinement with the turning portion 48 thereof whereby the blanks are held firm while said turning portions 48 bend or fold over the portions of the blank outwardly of the scoring 54.

The extreme inner ends of the plates 36 90 complete the folding over of the portions 46 and the blank is then progressed and before the second set of feed rollers relinquish their grip upon the blank, the next set engage the same. This third set of rolls has 95 the upper one formed with the wheels 30 and 31, and the beveled portions 32 of the wheels 31 engage the folded parts 46 to assist in turning the same down to insure their passing under the transverse member 100 43. The transverse member 43 creases the folds 46 and they then pass under the last set of rolls and are discharged from the machine in condition to be assembled and have the securing folds 46 secured in place 105 to form the assemble box.

What I claim as my invention is:

1. In a machine of the class described, fold forming means comprising a plate, means for feeding a blank past said plate with its adjacent edge portion engaging the same, a shoulder portion formed on said plate to fold the adjacent portion of the blank as it is fed past the plate, and means comprising a substantially rigid transverse 110 bar coacting with said plate to crease the blank at the fold.

2. In a machine of the class described the combination of a platform over which a box blank is adapted to pass; means for feeding said blank over said platform; a stationary plate having a twisted surface adapted to be engaged by a portion of said blank whereby said portion may be partially folded; and a substantially rigid bar 120 located adjacent the surface of said platform, adapted to engage said partially folded portion and complete its folding.

3. A machine for folding box blanks comprising a platform; means for feeding 130

blanks along said platform; a plate positioned adjacent each side of said platform and provided with a twisted surface adapted to be engaged by the edge portions of said blanks whereby said edge portions may be partially folded; a substantially rigid bar adapted to engage said partially folded edge portions and crease the same; and means for feeding said blank and edge portions beneath said bar.

4. A machine for folding box blanks comprising a platform; means for feeding blanks along said platform; a plate positioned adjacent each side of said platform and provided with a twisted surface adapted to be engaged by the edge portions of said blanks whereby said edge portions may be partially folded; a substantially rigid bar adapted to engage said partially folded edge portions and crease the same; and means comprising a pair of rollers each having a beveled face for feeding said blank and edge portions beneath said bar.

5. A machine for forming folds on blanks, comprising a platform, means for feeding blanks along the platform, a plate positioned adjacent each side of the platform

and engaging the adjacent edges of the blanks as they are fed therepast, fold forming means on the plate, and roller means engaging the blanks adjacent the crease of the fold to retain that part of the blanks adjacent the folds in engagement with the platform, a substantially rigid bar located transversely of said platform adapted to engage said edge portions and crease the same, and rotating means for feeding said blank and edge portions beneath said bar.

6. A machine for forming folds on blanks, comprising a platform, means for feeding blanks along the platform, a plate positioned adjacent each side of the platform and engaging the adjacent edges of the blanks as they are fed therepast, fold forming means on the plate, roller means engaging the blanks adjacent the crease of the fold to retain that part of the blanks adjacent the folds in engagement with the platform, and means comprising a substantially rigid transverse bar for pressing the folds as the blanks pass beyond the plates.

In testimony whereof, I affix my signature.

JACOB B. SCHMIDT.
